BLASTING CARTRIDGE

Frank H. Armstrong, Michigan City, Ind., assignor, by mesne assignments, to Safety Mining Company, Chicago, Ill., a corporation of Illinois

Application December 7, 1934, Serial No. 756,513

11 Claims. (Cl. 102—6)

This invention relates to blasting cartridges, and more particularly to blasting cartridges of the pre-charged type designed for use with a highly compressed gas as a blasting medium.

5 An object of this invention is to provide an improved blasting cartridge of the pre-charged type. Another object is to provide an improved blasting cartridge having improved release means for the blasting charge. A further object is to 10 provide an improved blasting cartridge of the pre-charged type wherein the same is pre-charged with high pressure gas of proper volume and at a proper pressure for the particular work at hand and then to suddenly liberate the charge by means 15 controllable at a remote point. Yet another object is to provide an improved pre-charged type blasting cartridge which may be transported from place to place with safety without possible danger of a premature discharge and which, when 20 positioned in blasting relation with the work, may be discharged at will by means controllable at a remote point. A still further object is to provide an improved blasting cartridge of the pre-charged type having improved heater release 25 means for developing a releasing pressure by means of heat generated in the cartridge subsequent to the positioning of the latter in blasting relation with respect to the work. Another object is to provide an improved heater release 30 means wherein the charge releasing pressure is developed by means of an explosive controllable at a remote point by electrical igniter means. These and other objects and advantages of the 35 invention will, however, hereinafter more fully appear.

In the accompanying drawing there are shown for purposes of illustration two forms which the invention may assume in practice.

In this drawing,—

40 Fig. 1 is a view in longitudinal section illustrating one form of the improved blasting cartridge.

Fig. 2 is an enlarged sectional view showing a modified form of discharge release means.

45 In both embodiments of the invention the improved discharge release means is shown associated with a blasting cartridge of the pre-charged type designed for use with a high pressure gas, such as highly compressed air, as a 50 blasting medium. The particular blasting cartridge with which the improved discharge release means is associated is of the same general type as that disclosed in my copending application, Serial No. 718,175, filed March 30, 1934 (see 55 Fig. 12), and is of the type designed to be charged

at some central charging point and then transported in a pre-charged condition to the point of use at which, after being placed in proper relation with respect to the work, a suitable discharge release device is attached to the cartridge 5 for effecting discharge thereof by remote control. The particular cartridge disclosed comprises an elongated cylindrical container 1 having a chamber 2 for receiving a charge of high pressure gas. Threaded at 3 within the inner end of the container is a discharge cap 4, while threaded at 5 within the outer end of the container is a control cap 6. Formed in the discharge cap 4 is an axial discharge orifice 7 communicating externally through a series of discharge ports 8. Seating on the inner end wall of the discharge orifice 7 is a conical discharge control valve 9 having an axial guide extension 10 which, with a bore 11 formed in the discharge cap, serves to center and guide the valve 9 with 20 respect to its seat. Reciprocable in the bore of a control chamber 12 in the control cap 6 is a plunger 13 having a valve rod 14 arranged axially within the pressure chamber 2 and secured at 15 at its inner end to the control valve 9. Secured 25 against the plunger body by a keeper 16 threaded on the valve rod is a cup leather 17 for permitting leakage of high pressure gas from the inner end of the control chamber past the plunger while preventing back flow of gas. Secured to the container by the control cap 6 and clamped in position between gaskets 18 is the flange of a stuffing box member 19 carrying packing 20 tightly engaging the exterior surface of the valve rod 14 to prevent leakage of pressure from the 30 pressure chamber 2 to the control chamber 12. A follower member 21 threaded within the member 19 is provided for tightening the packing 20. The valve rod 14 is axially bored at 22 and this bore 35 communicates through a passage 23 controlled by a spring pressed check valve 24 with the control chamber 12 at the outer side of the plunger 13 and through radial ports 25 with the pressure chamber 2.

The control cap 6 embodies a charging valve 26 for controlling a passage 29 communicating with an axial passage 30, the latter in turn communicating with the control chamber 12. The charging pressure flows past the valve 26 through passages 29 and 30 to the control chamber 12, the pressure acting on the outer pressure area of the plunger 13 to hold the valve 9 firmly against its seat. The charging pressure also flows through passage 23 past the ball check valve 24 through the bore 22 in the valve rod and radial ports 25.

to the pressure chamber 2, and when a predetermined blasting pressure is attained within the chamber 2 the charging valve 28 is closed in a suitable manner. The axial passage 30 may communicate with a passage 31 in a plug 32 threaded within the control cap, this plug holding in position a metallic washer 33 providing a seat for a spring pressed ball check valve 34 normally cutting off communication of the axial passage 30 with the vent passage 31. By means of the charging valve 28 a charge of high pressure gas may be introduced into the container chamber 2 at some central charging point, and the cartridge may be then transported as a self-contained unit to the point of use.

Associated with the blasting cartridge above described is a pressure release device generally designated 35 for effecting discharge of the cartridge which has been previously pre-charged, whereby when the blasting cartridge is properly positioned with respect to the work, the device 35 may be so controlled from a remote point as to effect blasting pressure release. The charge release device 35 shown in Fig. 1 consists of a casing 36 in which is positioned a plunger 37 having a stem 38 projecting inwardly through an opening 39 in a partition 40. This casing 36 is threaded connected at 41 to a threaded projection 42 formed on the control cap 6 of the cartridge, and when the casing is threaded on this projection there is provided a chamber 43 between the partition 40 and the outer surface of the projection 42, and this chamber is vented to atmosphere through radial vent ports 44. Interposed between a shoulder 45 on the plunger 37 and the partition 40 and encircling the plunger body and stem is a coil spring 46 for normally maintaining the plunger in its outermost, inactive position, and for automatically returning the plunger to such position after pressure release has taken place. Threaded at 47 within the outer end of the casing 36 is a firing cap 48 with which the plunger 37 in its outermost position engages. Secured within a recess 49 in the cap 48 is a container 50 for a suitable explosive 51, the container 50 projecting inwardly within a chamber 52 formed within the plunger body. Secured by a plug 53 threaded within the cap 48 is an electrode 54 connected through a wire 55 to a match head 56 embedded within the explosive 51 in the manner shown. This match head 56 is grounded by a wire 57 to the cap 48. Carried within the cap 48 is an electrical conductor connection 58 through which electrical energy is conducted to the electrode and thence to the wire 55 to the match head 56. The cap 48 is provided with a ground connection 59 and suitable wires lead from the connections 58 and 59 to a remote source of electrical energy.

The modification shown in Fig. 2 is substantially the same as that shown in Fig. 1 with the exception that the casing 60 has a bore 61 containing a reciprocable plunger 62 having a stem 63. The bore 61 at the inner side of the plunger 62 is vented to atmosphere through vent passages 64, and the explosive container 50 projects within the bore 61. It will thus be seen that the plunger chamber and coil spring of Fig. 1 have been eliminated in Fig. 2. Otherwise this form of the invention is similar to that above described.

In using a cartridge of the type illustrated, just prior to the positioning of the cartridge with respect to the work, the charge release device is threadedly connected to the projection 42 on the control cap 6 of the pre-charged cartridge. The

entire cartridge unit is then placed in blasting position with respect to the work and wires extended from the connections 58 and 59 of the charge release device to a suitable remote point of control. When electrical energy is conducted through the wires to the electrode 54 and thence to the match head 56, the explosive 51 in the container 50 is ignited and the explosion created thereby develops a relatively high pressure at the outer side of the plunger 37, thereby moving the plunger inwardly against the tension of the spring 46. As this plunger moves inwardly, the plunger stem 38 engages and unseats the ball check valve 34. The unseating of this valve causes the control chamber 12 at the outer side of the plunger 13 to be vented to atmosphere through passage 30, passage 31, chamber 43 and vent passages 44. The pressure in the control chamber 12 at the inner side of the plunger 13 then acts on the plunger to move the latter outwardly, and, as a result, the valve 9 is unseated to release the blasting charge through discharge orifice 7 and discharge ports 8. The pressure release means shown in Fig. 2 operates to effect discharge of the blasting pressure in a similar manner. These and other uses and advantages of the improved blasting cartridge will be clearly apparent to those skilled in the art.

While there are in this application specifically described two forms which the invention may assume in practice it will be understood that these forms of the same are shown for purposes of illustration and that the invention may be modified and embodied in various other forms without departing from its spirit or the scope of the appended claims.

What I claim as new and desire to secure by Letters Patent is:

1. In a pre-charged blasting cartridge, a container for receiving a pre-charge of highly compressed gas and having a discharge orifice, a differential valve mechanism for controlling said orifice, said container embodying a control chamber, the pressure wherein governs the position and movement of said differential valve mechanism, a connection through which compressed gas may be introduced into and exhausted from said control chamber, a valve governing said connection, and means subject to remote control for actuating said valve by creating with an explosive effect a relatively high, gaseous, valve actuating pressure.

2. In a pre-charged blasting cartridge, a container for receiving a pre-charge of highly compressed gas and having a discharge orifice, a differential valve mechanism for controlling said orifice, said container embodying a control chamber, the pressure wherein governs the position and movement of said differential valve mechanism, a connection through which compressed gas may be introduced into and exhausted from said control chamber, a pressure actuated valve governing said connection, and remote control means for unseating said valve to exhaust said control chamber to the atmosphere and including means embodied in the cartridge for creating with an explosive effect a relatively high, gaseous, valve actuating pressure.

3. In a pre-charged blasting cartridge, a container for receiving a pre-charge of highly compressed gas, discharge means for the charge of highly compressed gas, and means embodied in the cartridge and controllable from a remote point for governing said discharge means, said discharge means including a control chamber and

a reusable vent valve for venting the control chamber and said governing means including a self-contained pressure actuated device for unseating said vent valve.

5. 4. In a pre-charged blasting cartridge, a container for receiving a pre-charge of highly compressed gas, discharge means for the charge of highly compressed gas, means embodied in the cartridge and controllable from a remote point 5 for governing said discharge means, said discharge means including a vent valve and said governing means including a self-contained pressure actuated device outside said container for unseating said vent valve, and means for generating 10 a gaseous pressure for effecting actuation of said valve unseating means.

5. In a blasting cartridge, a container adapted to receive a charge of high pressure gas and having a release valve, means normally subjected to 20 pressure for maintaining said release valve closed and operative on release of such pressure to effect release valve opening and charge release, a valve movable against such pressure to effect release thereof, and means attached to said cartridge for generating a pressure and utilizing the same to open said last-mentioned valve.

6. In a blasting cartridge, a casing providing a pair of non-interconnected chambers, one for the storage of a charge of high pressure gas and 30 the other for the generation of a substantial pressure, charge operated discharge means for the high pressure gas chamber, means for effecting operation of said discharge means for releasing the charge of high pressure gas upon the generation 35 of such substantial pressure in the second chamber, and means for effecting pressure generation in said second chamber.

7. In a blasting cartridge, a container adapted to receive a high pressure charge and having a 40 discharge opening, valve means for closing said opening, fluid controlled releasable means for holding said valve means in said opening, a fluid controlling spring pressed vent valve for effecting operation of said releasable means, and means 45 operative from a remote point from the cartridge

for developing power to actuate said vent valve.

8. In a blasting cartridge, a container adapted to receive a high pressure charge and having a discharge opening, valve means for closing said opening, fluid controlled releasable means for holding said valve means in said opening, venting means for the fluid controlling said releasable means, and means operative from a remote point from the cartridge for developing power to actuate said venting means, said last-mentioned 10 means including a plunger, and an explosive charge for actuating said plunger.

9. In a pre-charged blasting cartridge, a container for receiving a pre-charge of highly compressed gas, differential pressure operated discharge means within the container for releasing the blasting charge, means containing an explosive attached to the cartridge in the charged condition of the latter for developing a releasing pressure by the ignition of the explosive charge, 20 and means controllable from a remote point for igniting the said explosive.

10. In a pre-charged blasting cartridge, a container for receiving a pre-charge of highly compressed gas, differential pressure operated discharge means within the container for releasing the blasting charge, means including a valve for producing the differential pressure necessary to operate said discharge means, and explosive means attachable to the cartridge in the charged 30 condition of the latter for developing the actuating pressure for said valve.

11. In a pre-charged blasting cartridge, a container for receiving a pre-charge of highly compressed gas, differential fluid pressure operated discharge means in the container for releasing the blasting charge, and electrically energized means embodied in the cartridge and controllable from a remote point for governing said discharge means while the container pressure remains constant, said electrically energized means including 40 devices for creating a differential fluid pressure condition which will operate the discharge means.

FRANK H. ARMSTRONG. 45
